US00D895527S

(12) **United States Design Patent** (10) Patent No.: **US D895,527 S**
(45) Date of Patent: ** Sep. 8, 2020

(54) **AERIAL VEHICLE**(71) Applicant: **SZ DJI Technology Co., Ltd.**,
Shenzhen (CN)(72) Inventors: **Jiadi Wang**, Shenzhen (CN);
Yongsheng Zhang, Shenzhen (CN);
Xingyuan Chen, Shenzhen (CN);
Liang Sun, Shenzhen (CN)(73) Assignee: **SZ DJI Technology Co., Ltd.**,
Shenzhen (CN)(**) Term: **15 Years**(21) Appl. No.: **29/623,118**(22) Filed: **Oct. 23, 2017****Related U.S. Application Data**(63) Continuation of application No. 29/547,032, filed on
Nov. 30, 2015, now Pat. No. Des. 820,768.(51) LOC (12) Cl. **12-07**

(52) U.S. Cl.

USPC ..... **D12/328**(58) **Field of Classification Search**USPC D12/1-4, 16.1, 319-345; D21/436-454;
D30/160
CPC B64C 39/024; B64C 13/16; B64C 19/00;

Primary Examiner — Marissa J Cash*(74) Attorney, Agent, or Firm* — Sterne, Kessler,
Goldstein & Fox P.L.L.C.(57) **CLAIM**The ornamental design for an aerial vehicle, as shown and
described.**DESCRIPTION**FIG. 1 is a top front perspective view of an aerial vehicle
showing the claimed design;

FIG. 2 is a rear view thereof;

FIG. 3 is a front view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the aerial
vehicle that form no part of the claimed design.**1 Claim, 7 Drawing Sheets**---
